UNITED STATES PATENT OFFICE.

RONALD MARSDEN HAMILTON, OF MALVERN, ENGLAND.

LAUNDRY TRANSPORT RECEPTACLE.

Application filed May 3, 1928, Serial No. 106,445, and in Great Britain April 17, 1926.

This invention has reference to "washing" charge systems, that is to say the method of and means for settling and determining charges or costs of variable quantities of 5 "washing" which are sent to and washed in laundries, by householders and other establishments; and it has primarily for its object and effect to provide an improved method or means by which the costs or charges of various 10 quantities of washing to be sent and done, would both to the customer and to the laundry man become satisfactorily and readily determined or fixed or made.

According to the present invention, the system 15 of charging is by bulk of the goods sent in a bag to the laundry; and while this bulk may vary week by week or other period, the invention nevertheless, that the right and fixed charge for a given quantity or 20 bulk of washing sent to the laundry, will always be automatically furnished by apparatus or means employed. Namely, under this invention or system, clothes or articles to be sent to the laundry, are filled into the bag, 25 and the bag has in connection with it a large number of straps, with buckles, clips, rings, cords or other suitable fasteners which go round it, and disposed in sequence in the direction of the length of the bag; and according 30 to the portion of the bag filled by the quantity of clothes to be sent, so will that strap, binder or fastener be selected which will close the bag directly above the point to which it is filled; each strap, binder or fastener 35 thus serving as an index of the quantity or bulk of clothes sent, and the charge associated with that index for such a quantity; and thus the bag apparatus automatically gives the washing cost of the parcel of goods.

40 For instance, when the bag is filled up to one strap, tie or binder level, the cost or charge of the wash will say be $1/-$, the next binder $1/6$, and the next $2/-$, and so on, or on any charge scale desired; and for the purpose hereinafter stated the spacings apart of 45 the straps, rings or bindings may be progressively greater from the bottom to the mouth of the bag. By this arrangement, inasmuch as the collection and office expenses are the same for each bag-full or bundle, and the 50 cost of a small bundle is greater proportionately than that of a larger bundle, the exact correct charges for all size of bulk can be obtained, so that the profit per cent of 55 turnover remains constant.

Instead of a plurality of straps or the like

being used, the bag may have a series of rings or loops on it, spaced apart as described; and a single buckle or clip strap may be used, and clipped or strapped onto or passed through 60 the ring or loop at the point just above the level of the bulk of things in the bag. Or similar or equivalent means may be adopted to attain the above end.

An example of the application or carrying 65 out of the invention is given in the annexed drawings, which shows a bag, say a textile bag, of equal diameter, closed at one end—the bottom—and open at the other—the mouth—and with differently spaced tying, closing, or 70 binding devices, and the cost or charges associated with same.

In the drawings, Figure 1 shows diagrammatically the bag empty and standing vertically on its bottom; Figure 2 shows the bag 75 with a batch of "washing" in it, ready to be collected and taken to the laundry; Figure 3 is a perspective view of a modified form.

In this drawing, 1 represents the bag proper, which may be of textile or any suitable material, and normally when empty it will lie flat or can be folded or rolled up, and 2 are the straps, ties, or binders of any suitable kind, one end of each of which in the case shown is secured in line vertically of the bag; 80 and associated with each of these straps or binders, say marked on the bag adjacent to each of them or as desired, is the charge representing the cost of the wash when the bag is filled and tied at that level or point, as 85 shown in Figure 2. Also in the case shown, the spacing of the straps, ties or bindings varies, i. e. increases progressively from the bottom.

The correct charges for all sizes of bulk 90 as above pointed out, being determined, the profit per cent of turnover remains constant.

With regard to the straps, ties or bindings, 95 these may be of leather, cord, banding, webbing, and may be fastened by buckles, clips, 100 tying or in any suitable way.

The modified form of packing, where at the points of closure rings or loops are used, is 105 illustrated in Figure 3. In this case a single strap will be used, and at the points of closure rings 3 are secured to the outside of the bag at points spaced apart, similarly as the straps 2 in Figure 1 are secured to the bag; and in connection with the various rings, a single loose strap is employed which will be passed 110 through the loop or ring 3 so as to close the bag at any point below which the bag will be

filled by the clothes or things to be sent, similarly as shown in Figure 2. This form of closing and fastening is thus the converse of that shown in Figures 1 and 2.

5 A further advantage of the apparatus arranged as described and shown is that the cost of multiples of bulk of washings, varies, namely, that the greater the bulk, the relatively less it costs per unit of quantity.

10 What is claimed is:—

A means for measuring laundry, consisting of a bag of flexible material having straight sides, the bottom of the bag being

the same size as the top, said bag being provided with price designations thereon spaced apart in the direction of the length of the bag 15 and each corresponding in amount with the price for a quantity of laundry filling the bag to the point where the designation is located, and means on the bag adjacent to each designation by which the bag can be closed at the particular point determined by such price designation.

In testimony whereof I have signed my name to this specification.

RONALD M. HAMILTON.
